UNITED STATES PATENT OFFICE.

ALFONS MOSCA, OF NORFOLK, VIRGINIA.

ICE-SHAVING MACHINE.

1,251,087.

Specification of Letters Patent. Patented Dec. 25, 1917.

Application filed October 5, 1914. Serial No. 865,170.

To all whom it may concern:

Be it known that I, ALFONS MOSCA, a citizen of the United States, residing at Norfolk, in the county of Norfolk, State of Virginia, have invented certain new and useful Improvements in Ice-Shaving Machines; and I do hereby declare the following to be a full, clear, and exact description of the invention, such as will enable others skilled 10 in the art to which it appertains to make and use the same.

This invention relates to ice shaving machines and particularly to a type adapted for finely shaving ice for use at soda fountains and the like.

The object of the invention resides in the provision of a machine of the character named embodying improved construction whereby the operation of same is rendered 20 rapid and effective and machines of this type simplified.

With the above and other objects in view the invention consists in the arrangement and combination of parts to be hereinafter 25 more fully described and particularly pointed out in the appended claims.

In describing the invention in detail reference will be had to the accompanying drawings wherein like characters of reference denote 30 corresponding parts in the several views, and in which—

Figure 1 is a plan view of an ice shaving machine constructed in accordance with the invention;

Fig. 2, a side view of what is shown in Fig. 1;

Fig. 3, a section on the line 3—3 of Fig. 2;

Fig. 4, an end view of the machine;

Fig. 5, a partial longitudinal section;

Fig. 6, a section on the line 6—6 of Fig. 3;

Fig. 7, a section on the line 7—7 of Fig. 2;

Fig. 8, a section on the line 8—8 of Fig.

1, and

Fig. 9, a view in elevation of the thread 45 block.

Referring to the drawings the improved ice shaving machine is shown as comprising a casing A formed of a bottom section 10 supported upon legs 11 and a top section 12 50 hinged to the bottom section at one side edge and provided with a handle 13 whereby said top section may be raised to afford access to the interior of the casing for the purpose of filling the latter with ice. One end

of the casing A is closed by a head 14 having a depending discharge mouth 15 through which latter the shaved ice is delivered into a suitable receptacle. The outer side of the lower end of said discharge spout embodies a separate plate 15' hinged at 16' and detachably fastened at 17' whereby access to the interior of the spout may be readily had for adjustment of the knives to be presently referred to. Rotatably mounted in the center of the head 14 is a shaft 16 which has 55 fixed on the inner end thereof a knife disk B upon which is mounted in a suitable manner a plurality of radially disposed knives 17, the disk B being provided with openings 18 through which the knives 18' project respectively. The disk B is further provided with an extended hub portion 19 having arms 20 and secured to the disk B in radial alignment with one of the arms 20 is a wing 21 adapted to sweep the interior of the head 14 60 during the rotation of the disk B. The periphery of the disk B is provided with teeth 22 for a purpose that will presently appear, the casing A being provided with an opening in its side wall at a given point through 65 which a gear 23 projects, the teeth of the latter meshing with the teeth 22. The gear 23 is fixed upon a shaft 24 journaled in a bearing 25 formed integral with the head 14. Also fixed upon the shaft 24 at the end thereof opposite the gear 23 is a gear 26 which 70 meshes with a gear 27 attached to a spindle 28 which latter is rotatably mounted upon a stub shaft 29 carried by the head 14. The spindle 28 is adapted to be rotated in any 75 suitable manner, either by hand or by suitable connection with a source of power.

Projecting laterally from the head 14 is a bearing 30, while another bearing 31 projects laterally from the opposite end of the 80 casing A and alines with the bearing 30. These bearings 30 and 31 support the terminals of a tubular member 32 which is provided on its under side with a longitudinal slot 33. Disposed within the tubular member 32 and rotatably mounted in the bearings 30 and 31 is a screw 34 the purpose of which will presently appear. Fixed on the end of the screw 34 adjacent the head 14 is a sprocket wheel 35 which alines with a 85 sprocket wheel 36 fixed on the shaft 16, and traveling on the sprocket wheels 35 and 36 is a sprocket chain 37 whereby the rotation

of the disk B during the operation of the machine will effect a desired rotation of the screw 34.

Slidably mounted within the casing A is 5 a pressure disk 38 which is constantly urged to the limit of its movement away from the knife disk B by means of a spring 39 one end of which latter is secured to the disk 38 and the other end thereof to a fixed part 10 40. The disk 38 is provided with a lateral extension 41 which projects through a slot 42 in the casing A and in which slot the extension 41 travels during movement of the disk 38. The free end of the extension 15 41 terminates in a sleeve 43 slidable on the tubular member 32. This sleeve 43 has an opening 44 in the bottom thereof which registers with the slot 33 in the member 32, said opening 44 being surrounded by a skirt 45. Movable mounted in the opening 44 is 20 a screw block 46, having a depending portion 47. This depending portion 47 is provided in its outer face with a groove 47' in which is slidably mounted one arm of an 25 L-shaped member 48', said arm having threaded therein a bolt 49' which projects through a slot 50' in the depending portion 47. Also threaded on the bolt 49' is a nut 51' which bears against the inner side of the 30 portion 47 and whereby the L-shaped member 48' may be clamped to the portion 47 in a desired adjustment. The other arm of the L-shaped member carries an adjusting screw 52' which is adapted to engage the bottom 35 edge of the portion 47 to limit the upward movement of the L-shaped member during adjustment of the latter relative to the portion 47. The bolt 49' also extends through a slot 49 in a depending arm 50 formed 40 integral with the sleeve 43. The screw block 46 is normally held out of operative relation to the screw 34 by means of a spring 51 mounted in the slot 49 and bearing at its lower end against the bolt 49' and at its 45 upper end against an end wall of the slot 49. Pivoted against the outer side of the sleeve 43 is a controlling handle 52 provided with a bottom extension 53 which overlies the arm 50. This extension 53 is provided 50 with a slot 54 through which the bolt 49' also projects. The slot 54 is so shaped that when the upper portion of the handle 52 is moved to its limit away from the head 14 the wall of the slot 54 will coöperate with 55 the bolt 49' to move the thread block 46 into operative engagement with the screw 34 and thus connect the sleeve 43 with said screw so that the rotation of the latter will move the disk 38 toward the disk B and force the 60 ice disposed between said disks against the disk B to be operated upon by the knives 17. When the upper portion of the handle 52 is moved a predetermined distance toward the head 14 the bolt 49', owing to the 65 shape of the slot 54, is released to the in-

fluence of the spring 51 and the thread block thereby shifted out of operative relation to the screw 34 when the spring 39 is free to act and return the disk 38 to the limit of its movement away from the disk B.

In order to automatically effect the disengagement of the screw block 46 from the screw 34 when the disk 38 has moved a predetermined distance toward the disk B there is formed on the bearing 25 an extension 70 55 in which is adjustably threaded a tripping member 56 adapted during the forward movement of the disk 38 to engage the extension 53 of the handle 52 and rock said handle to effect disengagement of the thread block 46 from the screw 34 in the manner previously described.

In order to hold the disk 38 at the limit of its movement toward the disk B against the influence of the spring 39 so that small 85 pieces of ice, if any, can be cleared away there is mounted on the head 14 a spring latch 57 adapted to engage over a nib 58 on the sleeve 43 just as the thread block 46 is disengaged from the screw 34. By tripping the latch 57 it will be obvious that the disk 38 can be returned to the limit of its movement away from the disk B under the influence of the spring 39.

In order to hold the ice against the action 95 of the knives 17 there is mounted upon the inner wall of the casing A a longitudinal wing 59 which slides in a recess 60 formed in the disk 38.

Assuming the disk 38 to be at the limit 100 of its movement away from the disk B a desired supply of ice to be shaved is deposited in the casing A between the disks 38 and B. This disk B is then rotated in the manner previously referred to which 105 will result in rotation of the screw 34. The handle 52 is then operated to engage the thread block 46 with the screw 34 when the disk 38 will be fed toward the disk B and the ice forced into engagement with the 110 knives 17. When the disk 38 almost reaches the knives 17 the extension 53 will be engaged by the member 56 and the thread block 46 disengaged from the screw 34. At the same time that this takes place the latch 115 57 will engage over the nib 58. Upon tripping the latch 57 the disk 38 will be moved to its initial position by the spring 39.

By providing the adjustable L-shaped member 48' it will be apparent that the bolt 120 49' can be also adjusted so as to take up wear of the thread block 46.

What is claimed is:—

1. In a device of the class described the combination of a frame, a threaded shaft 125 rotatably mounted on the frame, a member mounted for movement longitudinally of the shaft, a thread block slidably mounted on the member for movement into and out of engagement with the threads of the shaft,

- spring means normally holding the thread block out of engagement with the threads of the shaft, a lever pivoted on the member, connections between the lever and the thread block whereby the movement of said lever in one direction will operate the thread block into engagement with the threads on the shaft to effect movement of the member longitudinally of the shaft, and means on 5 the frame for engaging the lever when the member has moved a predetermined distance to rock said lever in the opposite direction and release the thread block to the influence of said spring means.
- 10 2. The combination of a frame, a slotted tubular member mounted in the frame, a threaded shaft rotatably mounted within the tubular member, a sleeve slidably mounted upon the tubular member, a threaded block 15 carried by the sleeve and movable in the slot of the tubular member into and out of threaded engagement with the screw and means for actuating the block.
- 20 3. The combination with a suitably mounted longitudinally slotted tubular member, of a feed screw therein, a sleeve slidably mounted upon the tubular member, a threaded block carried by the sleeve and movable in the slot of the tubular member into and out 25 of threaded engagement with the screw for movement of the sleeve under the influence of the screw, means for holding the block yieldably in engagement with the screw and means for automatically moving the block 30 from such engagement at a predetermined limit of movement of the sleeve upon the tubular member.
- 35 4. The combination with a suitably mounted longitudinally slotted tubular member, of a feed screw therein, a sleeve slidably mounted upon the tubular member, a threaded block carried by the sleeve and movable in the slot of the tubular member into and out 40 of threaded engagement with the screw for movement of the sleeve under the influence of the screw, means for holding the block yieldably in engagement with the screw, means for automatically moving the block 45 from such engagement at a predetermined limit of movement of the sleeve upon the tubular member, and means for automatically moving the sleeve under the influence of the screw, means for holding the block yieldably in engagement with the screw, means for automatically moving the block 50 from such engagement at a predetermined limit of movement of the sleeve upon the tubular member, and means for automatically returning the sleeve when the block is disengaged from the screw.
5. The combination with a suitably mounted longitudinally slotted tubular member, 55 of a feed screw therein, a sleeve slidably mounted upon the tubular member, a threaded block carried by the sleeve and movable in the slot of the tubular member into and out of threaded engagement with the screw 60 for movement of the sleeve under the influence of the screw, means for holding the block yieldably in engagement with the screw, potential means for automatically returning the sleeve when the block is disengaged from the screw, and means operative 65 prior to disengagement of the block from the screw to retain the sleeve temporarily against the action of the potential means.
6. The combination of a frame, a slotted 70 tubular member mounted in the frame, a threaded shaft rotatably mounted within the tubular member, a sleeve slidably mounted upon the tubular member, a threaded block 75 carried by the sleeve and movable in the slot of the tubular member into and out of threaded engagement with the screw, means for actuating the block, and means for adjusting the normal position of the block, with respect to the screw to compensate for 80 wear.

In testimony whereof, I affix my signature, in the presence of two witnesses.
